UNITED STATES PATENT OFFICE.

DAVID KAHNWEILER, OF NEW YORK, N. Y.

LIFE-RAFT.

SPECIFICATION forming part of Letters Patent No. 421,578, dated February 18, 1890.

Application filed October 26, 1889. Serial No. 328,332. (No model.)

To all whom it may concern:

Be it known that I, DAVID KAHNWEILER, a resident of the city of New York, county and State of New York, have invented Improvements in Life-Rafts, of which the following is a specification.

This invention relates to the class of life-rafts in which tubes or cylinders are used to support or buoy up the frame-work or platform of the raft, and it has for its object to connect the frame-work or platform of the raft with the tubes or cylinders in such manner that said tubes or cylinders will not be injured or permitted to leak by their connection with the frame-work or platform.

The invention consists in the novel details of improvement and combinations of parts that will be more fully hereinafter set forth, and then specifically designated in the claims.

Reference is to be had to the accompanying drawings, forming part of this specification, wherein—

Figure 1 is a plan view of a life-raft embodying my invention. Fig. 2 is a vertical longitudinal section of the same on the line *h h*, Fig. 1. Fig. 3 is a vertical cross-section on the line *c c*, Fig. 1; and Fig. 4 is a detail view of the end of one tube or cylinder.

The letter *A* in the accompanying drawings indicates a tube or cylinder of ordinary construction, preferably tapering at both ends, and adapted to float upon the water. The tubes or cylinders *A* may be provided with several air-tight compartments if desired.

Fig. 1 shows two tubes or cylinders *A* as being used to constitute a complete life-raft. Between these two cylinders *A* is a suitable frame-work or platform *B*, to which said tubes or cylinders are secured. Heretofore the tubes or cylinders have been secured to the frame-work or platform by means of bolts or the like secured to and projecting from said cylinders, or by angle-irons connected to said cylinders by rivets or the like; but I find with said constructions that through rust or wear from shocks or the like the bolts become loosened from the cylinders, or water is permitted to pass into the cylinders around said bolts, whereby the usefulness of the life-raft is greatly diminished. By my invention I connect the cylinders *A* with the frame-work or platform *B* by means of clamps, so that I

totally avoid the use of bolts or angle-irons that are riveted to the cylinders.

Referring now to Fig. 3, the sides of the frame-work *B* or the cross-beams *B*² thereof that come against the cylinders *A* are curved or hollowed out, as at *a*, to fit the curves of the cylinders, as shown.

D are bands that are placed on the outer sides of the tubes or cylinders *A*, diametrically opposite the curves *a* of the frame-work *B*, and these bands on the opposite cylinders are connected together by means of cross-rods or the like *E*, as clearly shown in Fig. 3. By this means the tubes or cylinders *A* are held as in a clamp between the frame-work *B* and the bands *D*. There may be several bands *D*, as shown, for each cylinder, the opposite bands being connected together above and below the frame-work by the rods or the like *E*. I prefer that the rods *E* be screw-threaded at their ends and provided with nuts *b*, whereby the parts may be firmly clamped together and any looseness taken up as it may occur.

In order to additionally strengthen the parts, I prefer to place longitudinal bars *F* along the sides of the cylinders, which bars are secured to the bands *D*, as clearly shown in Fig. 3. I pass the bolts or rods *E* through the bars *F* on the upper and lower sides of the cylinders *A*, as well as through the bands *D*, as shown in Fig. 3, whereby the whole structure is materially strengthened.

By the above arrangement of parts it will be seen that no rivet-holes are made in the cylinders for the purpose of connecting them to the frame-work, they being merely held to the frame-work by clamps or pressure, so that danger of their becoming injured through strain on the bolts or the connections between the cylinders and the frame-work is overcome.

In order to prevent the bands *D* at the ends of the cylinders slipping off the same, or, in other words, to prevent the cylinders becoming disconnected from the frame-work of the raft by slipping between said frame-work and the bands, and to prevent the necessity of securing the bands to the cylinders by rivets, or the like, I place the ends of the cylinders within the tapering or cone-shaped cap *d*, as shown in Figs. 1 and 4. By this means a shoulder or projection *e* is formed on the

outer sides of the cylinders, whereby longitudinal movement of the cylinders within the frame-work and bands is prevented; but the tubes or cylinders may be expanded at 5 their ends, if preferred, to prevent, in connection with the clamping-bands D, sliding movement of the tubes A, in manner similar to the shoulders e. Of course the cap or cover d will be riveted to the cylinders, as 10 shown; but these rivets, it will be seen, do not act in any manner to connect the cylinders with the frame-work, and therefore no strain comes upon said rivets.

To additionally strengthen the parts of the 15 frame-work, I connect the upper and lower cross-rods E, about midway of their length, with the frame-work or platform B, by means of tie-rods f, as shown in Figs. 2 and 3. In said figures the tie-rods f pass through cross- 20 pieces g, that are on the inner side of the planks or bars h of the frame-work B, the outer ends of the tie-rods f being turned around the bars E, as indicated; but, if preferred, the bars E on the upper and lower 25 sides of the life-raft could be connected by a single tie-rod.

i are oar-locks carried on the rods f and the frame-work B, for use in propelling the life-raft. J are life-ropes suitably connected

with the life-raft, as shown. The bars F², 30 parallel with the bars F and secured to the bands D, act as fenders for the cylinders.

Having now described my invention, what I claim is—

1. The combination of the cylinders A and 35 the frame-work B, fitted between said cylinders, with the clamping-bands D, and the longitudinal strengthening-bars F, connected to said clamping-bands, and the cross-rods E, extending through the bars F from the clamping-bands of one cylinder to the clamping-bands of the next cylinder, whereby the parts 40 are held rigidly together, as specified.

2. The tubes or cylinders A, and the frame-work B between them, combined with the 45 clamping-bands D on the outer sides of said cylinders, rods E, connecting the clamps on the outer sides of the opposite cylinders, the longitudinal bars F, placed on the cylinders and traversed by the rods E, and the tie-rods f, connecting the rods E with the frame B, substantially as described, and for the purpose specified. 50

DAVID KAHNWEILER.
